UNITED STATES PATENT OFFICE.

RICHARD WEBB BURNETT, OF ALBANY, NEW YORK.

CAR-ROOF.

1,351,411.

Specification of Letters Patent. Patented Aug. 31, 1920.

Application filed February 9, 1918. Serial No. 216,177.

To all whom it may concern:

Be it known that I, RICHARD WEBB BURNETT, a citizen of the United States of America, residing at Albany, in the county of Albany and State of New York, have invented certain new and useful Improvements in Car-Roofs, of which the following is a specification, reference being had therein to the accompanying drawings.

10 The invention relates to car roofs of that type in which the roofing sheets are arranged beneath channel carlines and comprise the peculiar construction of roofing sheets which with the carlines form a thorough weather-
15 proof means and are practically self-sup-
porting. Another feature of the invention
is the means for further weatherproofing
the joint between the roofing sheets and at
the same time preventing abrasive action
20 between the carlines and roofing sheets.
Other features reside in the novel arrange-
ment and combination of parts, more fully
hereinafter described.

In the drawings:

25 Figure 1 is a fragmentary sectional side elevation through the car roof;

Fig. 2 is a fragmentary perspective view of the roofing sheets;

30 Fig. 3 is a similar view showing modified construction.

A is the carline of inverted channel or U-shaped cross section, having the outwardly-extending flanges, A' and B are the roofing sheets extending from eaves to eaves and provided on their opposite edges with the upstanding flanges B' arranged within the channels of the carline. The adjacent upstanding flanges of the adjacent roofing sheets are formed with the portions C and C' returnbent in the same direction and nested, the free ends of the returnbends being adjacent to each other. This arrangement will cause any moisture blown along the sheets beneath the carline and up the sheet flanges to be deflected away from the joint instead of being forced thereinto.

For the purpose of making the roofing sheets practically self-supporting, the free ends of the returnbends C and C' are secured 50 to each other, so that the stress upon the sheet having the lower returnbend C will be carried into the sheet having the upper returnbend C'. In other words, the construction is such that the sheets work together to 55 carry the load upon either or both. Fig. 2 shows these ends crimped together as at

D, while Fig. 3 shows them riveted together as at E.

For further weatherproofing the joint between the roofing sheets and at the same time for preventing abrasive action between the carline and roofing sheets in their relative movements, I provide a non-abrasive material F, preferably a strip of felt between the carline and roofing sheets, and extending continuously from one edge of the carline to the opposite edge. With this arrangement, any moisture that enters between the carline and the non-abrasive material can not reach the joint between the roofing sheets.

What I claim as my invention, is:

1. In a car roof, the combination with an inverted channel-shaped member, of load sustaining roofing sheets supported at spaced 75 points and arranged beneath said inverted channel-shaped member and having up-standing flanges adjacent to each other, the upper portions of said flanges being returnbent in the same direction, nested and se- 80 cured to each other at approximately the free edges.

2. In a car roof, the combination with an inverted channel carline, of load sustaining roofing sheets extending from eaves to 85 eaves of the car roof, said roofing sheets ar- ranged beneath said carline and having ap- standing flanges adjacent to each other, the upper portions of said flanges being returnbent in the same direction and nested, and 90 the free ends of said return-bends being crimped together at the edges.

3. In a car roof, the combination with an inverted channel-shaped member, of load sustaining roofing sheets supported at spaced 95 points and arranged beneath said inverted channel-shaped member and having up-standing flanges adjacent to each other, the upper portions of said flanges being returnbent in the same direction and nested, and 100 means securing said flanges to each other at approximately the free edges so that the stress upon the sheet having the lower re- turn-bent portion will be transmitted into the sheet having the upper return-bent por- 105 tion.

4. In a car roof, the combination with an inverted channel carline, of load sustaining roofing sheets extending from eaves to eaves of the car roof, said roofing sheets being ar- ranged beneath said carline and having up- 110 standing flanges adjacent to each other, the

upper portions of said flanges being return-bent in the same direction, nested and secured to each other near their edges, and a strip of felt between said carline and roofing sheets, extending continuously from one edge of the carline to the opposite edge thereof.

5. In a car roof, the combination of load sustaining roofing sheets supported near their opposite ends, said sheets provided with upstanding flanges adjacent to each other having their upper portions return-bent in the same direction, nested and secured to each other, whereby a load upon 10 either sheet will be transmitted into the other sheet, and a cap embracing said up-standing flanges.

6. In a car roof, the combination with an

inverted channel-shaped member, of roofing sheets arranged therebeneath and having 20 upstanding flanges adjacent to each other, the upper portions of said flanges being return-bent in the same direction and nested, and means for securing the edges of said flanges to each other at spaced points. 25

7. In a car roof, the combination with an inverted channel-shaped member, of roofing sheets arranged therebeneath and having upstanding flanges adjacent to each other, the upper portions of said flanges being 30 return-bent in the same direction and nested, and separate or displaced indentations near the edges of said flanges for securing the same to each other.

In testimony whereof I affix my signature. 35
RICHARD WEBB BURNETT.
